DESIGN FOR AN AMUSEMENT DEVICE

Harry D. Porter, Peoria, Ill.

Application June 28, 1935, Serial No. 57,443

Term of patent 3½ years

To all whom it may concern:

Be it known that I, Harry D. Porter, a citizen of the United States, residing at 1406 Sheridan Road, in the city of Peoria, in the county of Peoria and State of Illinois, have invented a new, original, and ornamental Design for an Amusement Device, of which the following is a specification, reference being had to the accompanying drawing, forming part thereof.

Fig. 1 is a perspective view of an amusement device, showing my new design, and

Fig. 2 is an enlarged fragmentary view illustrative of the manner of designating the peripheral portions of the circle, as the same would appear if taken on the bracketed portion 2—2 of Fig. 1.

I claim:

The ornamental design for an amusement device, substantially as shown.

HARRY D. PORTER.
